UNITED STATES PATENT OFFICE.

HOWARD W. MATTHEWS, OF LANSDALE, PENNSYLVANIA, ASSIGNOR TO DEXDALE HOSIERY MILLS, OF LANSDALE, PENNSYLVANIA, A CORPORATION OF PENNSYLVANIA.

YARN-CUTTING MEANS FOR KNITTING MACHINES.

Application filed October 22, 1926. Serial No. 143,330.

This invention is concerned with means useful for cutting float or other yarns projecting from the fabrics produced by knitting machines, and, more particularly to machines of the circular type ordinarily employed in the manufacture of hosiery and the like.

In the fabrication of knit products on machines of the kind referred to, it is customary to employ, in addition to a main or body yarn, other auxiliary yarns either for reinforcement or plating; and when only partial reinforcement or figurative plating is practiced, the loose strands of the auxiliary yarns are floated between those sections in which they are incorporated or interknit with the fabric.

The main objects of my invention are to enable cutting of such float yarns incident to the knitting of each course of the fabric by the machine; and to provide a very simple and reliable means for the purpose. This desiderata I attain through provision of a cutting means normally operative as a web holder but characterized by a cutting edge adapted to be thrust inwardly to cut float yarn spanning the interval between the corresponding pair of cooperating needles as a result of rapid movement imparted to such special web holder by a supplemental cam associated with the web holder actuating mechanism of the machine.

In the drawings herewith, Fig. I is a broken fragmentary axial section through the needle cylinder of a circular knitting machine equipped with the yarn cutting means of my invention.

Fig. II is an invert plan view of the cap ring providing the cam groove for actuating all the web holders.

Figs. III, IV and V, are diagrammatic detail views showing successive steps in the operation of the special yarn cutting web holder; and,

Fig. VI is a diagrammatic plan view of the parts positioned as in Fig. V.

The needle cylinder herein designated 5 will be observed as of standard tubular form with longitudinal surface grooves 6 to guide vertical movement of the needles 7. These needles 7 may be of the spring beard type; and means in the form of presser bits 8 are provided to actuate the needle beards incidental to the knitting of fabric in a well known

way. About the top of the needle cylinder 5 is secured a flange annulus 9 with radial grooves for reciprocative guidance of the usual web holders 10 as well as the special web holder 10^a (to be later on described in detail) in the intervals between adjacent knitting needles. The butts 11, of the web holders 10, 10^a, engage the actuating cam groove 12 of a cap ring 13, surmounting the flange annulus 9 with capacity for independent rotation thereon; while the inner ends of said web holders 10, 10^a, afford loop drawing ledges 14 and web engaging notches 15 which latter are overhung by retaining nibs 16. During operation of the machine, relative rotation as between the needle cylinder 5 and the cap ring 13 is attended by temporary retraction of the web holders 10, 10^a from the normal web retaining position at the stitch forming regions A, B, in Fig. II, to permit feeding of the yarn Y to the needles 7 during the rotary as well as the oscillatory phases of the knitting after common practice in this art.

Now it will be noted that the special web holder 10^a (of which there may be several interposed in the series 10) differs from the others in that it has an integral projection 17 upstanding from its nib 16, the inner vertical edge of this projection being beveled to the form of a knife edge 18, as seen to best advantage in Fig. VI. For the purpose of imparting a sudden inward cutting thrust to the auxiliary web holder 10^a, I equip the cap ring 13, at a convenient circumferential point, with a supplemental cam 19 characterized by a rather sharp and abrupt protuberance 20 that projects into the concentric portion of the cam groove 12, see Fig. II.

The operation of my invention will be best understood by reference to the diagrammatic illustrations of Figs. III, IV, V and VI. In being acted upon by the cam groove 12 at the regions A, B (Fig. II), the special web holder 10^a is retracted, as shown in Fig. III, to enable the needle 7 to descend and carry the body yarn Y through the terminal loop 7 of the preformed fabric F thereby to draw a loop for a successive course, the retaining nib 16 with its cutting lug or projection 17 being at this time well out of the way so as not to interfere with the described loop forming action. Immediately upon completion of the new fabric loop, the special web holder 10^a is advanced (in concert with its fellows 10)

by the cam groove 12 to engage the fabric within its notch 15 and prevent lifting thereof while the needle 7 rises, thus performing all the functions of an ordinary web holder.

5 10. In cases where an auxiliary or plating yarn Y'—for example—is floated, the same, instead of being drawn down by the needle 7, remains resting on the top of the nibs 16 of the web holders 10 as shown in Fig. IV, and, 10 although pressed inward by the projection 17 of the special web holder 10*, as the butt 11 of the latter enters the concentric portion of the cam groove 12, is not actually cut. However, when the special web holder 10* is engaged by the supplemental cam 19, the motion imparted is attended by a sudden inward thrust of the cutting projection 17, which results in severance of the float yarn Y' centrally of the span between the two needles 7 20 cooperating with said web holder, as shown in Figs. V and VI. Although the supplemental cam 19 also acts on the web holders 10, it has no effect other than to cause slight dilation of the fabric loops *l* successively, and, 25 since such action occurs at a localized point, loop compensation is allowed to take place immediately beyond the province of said cam, thereby offsetting any possibility of harm to the fabric F.

20 30. In order to enable compensation for wear from time to time, the supplemental cam 19 is made positionally adjustable through provision of a radial slot 21 in the cap ring 13 for passage of the securing clamp screw 22, see Figs. I and II.

40 From the foregoing, it will be obvious that my special web holders 10* may be employed in any number, i. e. at different locations corresponding to the regions at which the segments of the auxiliary or plating yarn Y' are floated; and, moreover, that my invention is exceedingly simple, and readily applicable to existent knitting machines without requiring any alteration whatever either in their 45 construction or normal mode of operation.

Having thus described my invention, I claim:

50 1. The combination with the needles of a knitting machine, of a knife edge means subject to sudden inward thrusts and occupying the interval between a pair of adjacent needles, and means for imparting such rapid

thrusts to the knife edge means to sever float yarn spanning the interval aforesaid before loop formation could take place.

55 2. The combination with the needles of a knitting machine, of means subject to predetermined abnormal inward thrusts in the interval between a pair of adjacent needles to cut float yarn spanning such interval previous to possible loop formation and at a level above that at which the preceding fabric loops are drawn.

60 3. The combination with the needles of a knitting machine and cooperating web holders having retaining nibs overhanging web engaging notches, of special means operable in intervals between pairs of adjacent needles with a sudden inward thrust to cut float yarn spanning such intervals above the 70 web holder nibs.

65 4. The combination with the needles of a knitting machine and cooperating web holders having retaining nibs overhanging web engaging notches, of special web holders 75 with upstanding knife projections adapted upon a sudden inward thrust to cut float yarn spanning the intervals between corresponding pairs of needles above said nibs.

70 5. The combination with the needles of a knitting machine, cooperating web holders having retaining nibs overhanging web engaging notches, and web holder actuating cams; of a special web holder having an upstanding knife edge, and a supplemental cam for imparting an abnormal rapid inward thrust to the special web holder thereby to effect severance of float yarn spanning the interval between the corresponding pair of needles by the cutting edge aforesaid.

75 6. As a new article of manufacture a special web holder adapted for co-operation between adjacent needles of a knitting machine, said web holder being characterized by a web engaging notch with an overshot retaining nib and a projection upstanding from said nib with a knife edge adapted for cutting float yarn incident to an inward thrust imparted to said holder.

80 In testimony whereof, I have hereunto signed my name at Lansdale, Pennsylvania, this 19th day of October, 1926.

HOWARD W. MATTHEWS.
